UNITED STATES PATENT OFFICE.

VIRGINIUS Z. CARACRISTI, OF BRONXVILLE, NEW YORK, ASSIGNOR TO LOCOMOTIVE
PULVERIZED FUEL COMPANY, A CORPORATION OF DELAWARE.

COMBUSTION METHOD AND APPARATUS.

Application filed December 23, 1922. Serial No. 608,626.

My invention relates to combustion methods and apparatus. The invention is concerned with the burning of diverse fuels in one and the same furnace, and especially 5 with the burning of pulverized fuel (such as powdered coal) in conjunction with other fuel, particularly fuel gas. I aim, in particular, to secure certain advantages as respects the operation of the furnace and the 10 combustion of both fuels by burning other fuel in conjunction with powdered coal.

How these and various other advantages can be realized through my invention will 15 appear from my description hereinafter of the best way of carrying out the invention now known to me which is illustrated by the accompanying drawing.

The figure shows a somewhat diagrammatic vertical section through a steam boiler furnace, illustrating the application of my 20 invention to this field of use.

The principal combustion zone of the furnace here shown is in a chamber 1 at the left-hand side of the boiler setting, with one 25 or more pulverized fuel burners 2 for directing a fuel and air stream 3 downward therein, adjacent the front wall 4, and with exit upward and toward the rear, at 5, into the boiler space 6 at the right-hand side of the 30 setting. In the front wall 4, at various heights, are damper-controlled intakes 7 through which additional air can be admitted, to aid combustion of the fuel and to form a sort of cooling blanket in front of the descending stream 3, for protecting the 35 wall from the intense heat. The flaming air and fuel stream 3 descends in the front of the combustion chamber 1 till its momentum is overcome by the draft and the accretions 40 of air introduced at 7, and then reverses and ascends in the rear of the combustion chamber to the exit at 5. Passing into the boiler space 6 in the right-hand side of the setting, the products of combustion traverse 45 the heating surfaces of the boiler (here shown as a water tube boiler of the Stirling type), and finally escape through the damper-controlled opening 10 into the flue 11 leading to the stack.

In practice, the draft and the fuel and air 50 admission at 2 and 7 are generally so regulated and correlated that the air and fuel stream 3 bends rearward and upward at such a height as to afford (as here shown) a 55 cooling zone 12 in the bottom of the com-

bustion chamber 1. As a result, falling particles of ash or slag are cooled below fusion temperature before they reach the furnace floor 13, so that they do not coalesce and run together into a hard, solid mass, but 60 remain loose and easy to remove. Cooling in this zone 12 may be effected largely by a sort of cooling blanket formed beneath the stream 3 (or beneath its descending column, especially) by the air introduced at 7. 65

As here shown, provision is made for burning fuel gas in the furnace, in combination with the powdered fuel. For this latter purpose, fuel gas introduced by means of a gas burner 15 (usually along with more 70 or less air for combustion) may be allowed to come in contact and mingle with the pulverized fuel stream 3, and join in its combustion. Preferably, this fuel gas is introduced beyond the air blanket from the intakes 7. In the present instance, the gas burner 15 is arranged to direct the fuel gas 75 into the lower region of the combustion chamber 1 in a lateral stream 16, beneath and against the pulverized fuel stream 3 at 80 the region of flexure of the latter. As shown, the fuel gas burner 15 discharges from the rear of the combustion chamber forward, through an auxiliary chamber 17 situated in the right-hand side of the boiler setting, directly under the boiler space 6. This auxiliary chamber 17 is separated from 85 the superjacent boiler space by a refractory arch 18 (surmounted by a sort of bridge wall 19 that shelters the lower boiler drum), and opens into the lower region of the combustion chamber 1 from the rear side of the latter. The fuel gas stream 16 thus introduced by the burner 15 issues from the chamber 17 against the lower side of the 90 ascending pulverized fuel stream 3, counter to the rearward movement of the latter (and its subjacent blanket of air from the intakes 7) at and beyond the point of flexure or reversal.

It will be seen, therefore, that the relatively cool gas stream 16 serves as a continually renewed cool blanket beneath and behind the flaming powdered fuel stream 3, chilling the falling slag and ash particles 100 (and thus increasing the effectiveness of the cooling zone 12), and also protecting the rear wall of the combustion chamber at 19. When this stream 16 is introduced from the rear, as here shown, its cooling power is 105 110

naturally greatest in the rear portion of the cooling zone 12 (beneath and behind the ascending column of the flaming stream 3), in the very region where the cooling blanket 5 formed by the air admitted at 7 tends to become ineffective. Moreover, this accretion of fuel to the stream 3 at this point allows more liberal admission of air at the lower intakes 7, so as to assure an ample 10 blanket of cool air beneath the descending column of the stream 3, in front of the gas stream blanket 16.

As to the gas stream 16 itself, it is first heated and ignited by incandescent particles of coal and slag falling into it from the powdered fuel stream 3 (as well as by conduction and radiation), so that when it actually encounters the stream 3, the gas is already burning. Striking the rear side of 20 the air and powdered coal stream 3 more or less at right angles, as it does, the gas stream 16 exerts a drag on this side of the stream 3. Thus swirls and eddies are set up in and beyond the junction, and thorough intermix- 25 ture of the air, gas, and incandescent solid particles is brought about.

The character of the stream 16 may vary considerably: thus it may consist, on the one hand, of a very rich gas; or, on the other hand, of a low-grade gas,—so poor in combustible constituents, even, as to be incapable of burning by itself without the regenerative heating and recurrent ignition effect of the falling incandescent fuel and ash or slag particles, the flaming stream 3, or the hot refractories of the furnace setting at 13, 18, 19, etc. In some cases, the fuel gas stream 16 may include a more or less adequate supply of air for combustion of the gas; in other cases (especially when the fuel gas is poor or diluted with inert constituents), reliance may be placed mainly on the air blanket from the intakes 7 for the combustion of the gas of the stream 16.

45 What I claim is:

1. The method of burning pulverized fuel in conjunction with other fuel, which com-

prises directing a pulverized fuel stream downward at one side of a combustion chamber having an outlet in an upper part, to 50 descend therein and then rise to said outlet; introducing air at the same side of said combustion chamber as said pulverized fuel stream, to form a cooling blanket in front of and beneath the descending portion of 55 said stream below the lowest level of air admission as aforesaid, and to aid combustion; and introducing another fuel stream, to form a cooling blanket beneath and behind the ascending portion of the pulverized fuel 60 stream, and to join in the combustion of the latter.

2. Apparatus of the character described comprising a combustion chamber with an outlet in an upper part for products of combustion; means for introducing a downwardly directed pulverized fuel stream, to descend at one side of the chamber, and for turning it upward to said exit; means for introducing air at the same side of said 65 chamber as said pulverized fuel stream, to form a cooling blanket in front of and beneath the descending portion of said stream, and to aid combustion; and means for introducing another fuel stream into the opposite side of the chamber, to form a cooling blanket beneath and alongside of the ascending portion of the pulverized fuel stream, and to join in the combustion of the latter.

3. Apparatus of the character described comprising a combustion chamber with an outlet in an upper part for products of combustion; means at one side of the chamber for introducing a downwardly directed 75 stream of pulverized coal and air for combustion, to descend therein, and for turning it upward to said outlet; and means for introducing a stream of fuel gas from the other side of the chamber.

In testimony whereof, I have hereunto signed my name.

VIRGINIUS Z. CARACRISTI.
